HELICOPTER OR SIMILAR AIRCRAFT

Robert R. Anderson, Palo Alto, Robert C. Herda, Portola Valley, Stanley Hiller, Jr., Atherton, Edward H. Jacobsen, Menlo Park, John B. Nichols, Atherton, and Sydney S. Sherby, Los Altos Hills, Calif., assignors to Hiller Aircraft Corp., Palo Alto, Calif., a corporation of California

Filed Apr. 17, 1961, Ser. No. 64,783

Term of patent 14 years

(Cl. D71—1)

F i g. 4

F i g. 3

F i g. 5

FIG. 1 is a side elevational view of a helicopter illustrating the design hereof;

FIG. 2 is a top plan view;

FIG. 3 is a front elevational view;

FIG. 4 is an isometric view of the helicopter as it appears in flight, looking at one side toward the rear;

FIG. 5 is a view similar to FIG. 4, looking at the opposite side toward the front.

Portions of the rotor blades are broken away in FIGS. 1, 2, 4 and 5 for convenience of illustration.

The full lines in the drawing illustrate the essential features of the design.

We claim:

The ornamental design for a helicopter or similar aircraft, substantially as shown and described.
